TOE SOFTENER

Charles Earl Martin, Binghamton, N. Y., assignor to Endicott Johnson Corporation, Endicott, N. Y., a corporation of New York

Application November 11, 1937, Serial No. 174,115

18 Claims. (Cl. 12—1)

This invention relates to heaters for softening box toe stiffeners in connection with the pull over and bed lasting operations in the manufacture of shoes.

5 In the toe softening operation the elements to be considered are the box toe material, the upper leather of the shoe and the insole, and in some cases a lining of sheepskin or a lining having a coating of material which will become sticky if overheated.

10 Box toe material can be softened in a dry heated atmosphere, but dry heat is injurious to the upper leather and innersole materials, and cannot be safely applied to an assembled shoe. Furthermore when dry heat is used the composition with which the box toe is impregnated will 15 fry out in the form of drops and beads on the surface of the material and this impairs the resultant structure.

20 In the manufacture of shoes, when the shoe comes to the "bed laster" the upper is "pulled over" the last and secured by tacks located on each side and at the extreme tip; the upper then hanging down around the forepart of the last 25 except when secured by the tacks, and such pulled over upper tends to spring away from the last, and this exposes much of the inside of the box toe stiffener and lining.

20 One object of my invention is to provide novel means whereby the box toe, upper leather, and lining can be readily softened to a degree that enables them to be easily formed or "lasted" without injury to the materials, and present a smooth unwrinkled appearance when the job is completed. A further object is to enable the box-toe to be softened without injuring the insole and upper portion of the shoe by either burning or wetting.

30 The accompanying drawings illustrate one embodiment of my invention, and I will first describe the same in detail with reference to said drawings; and then summarize in the claims the novel features of construction and novel combinations of parts for which protection is desired.

35 In said drawings:

Fig. 1 is a front elevation of my softener partly in section;

Fig. 2 is a detail vertical section on the line 2—2, Fig. 1;

50 Fig. 3 is a side view of Fig. 2;

Fig. 4 is an enlarged bottom plan view of the base plate and expansion chamber; and

Fig. 5 is a perspective view of part of the radiator.

55 In the construction shown a hollow standard 1

is mounted upon a support 1a of any suitable construction. On the upper end of standard 1 is mounted a base plate 2, having a central depending collar 2a, which is provided with an internal partition 2e, which closes off the upper 5 portion of the collar. The end of the collar below the partition is engaged with the upper end of standard 1, and supports the base plate thereon.

On the underside of the base plate, adjacent the rear edge thereof, is a hollow member 2b 10 (preferably cast integral with the base plate) having its bottom portion sloping inwardly and downward from its ends towards its center. The interior of member 2b forms a steam expansion chamber E. At its central portion this chamber 15 opens into the chamber in collar 2a above the partition 2e; the chamber in the upper part of the collar above the partition forms an extension of the expansion chamber E. To the partition 2e is connected a vapor outlet pipe 2o 20 which depends into the hollow standard 1, its lower end being below the level of the water therein, and being sealed by the water in the standard. In collar 2a below partition 2e are openings 2p which serve as vents for escape of 25 steam if the water seal is broken.

20 Mounted upon the base plate 2 is a radiator 4, which is preferably formed of a hollow casting having a plurality of integral exterior fins 4a 30 that extend at right angles to the radiator across the top and partially down each side thereof. The fins increase the heat radiation, and the spaces therebetween provide continuous vertical and horizontal passageways for heated air and vapor.

35 The radiator has end flanges 4b which extend entirely around the radiator and support it on and above the plate 2 and space it from the walls of the casing 3.

30 The radiator is surrounded by a casing 3 40 mounted upon the plate 2 and open at top and bottom. This casing forms the outside walls of the air passages between the fins 4a, and the upper edge of the casing is preferably provided with an offset flange 3a to receive the hood 5. 45

The hood 5 is preferably formed of a casting corresponding in length to the radiator, and having its front wall 5a curved downwardly from the top and rear of the hood to the front lower edge thereof, and in this curved wall are formed 50 openings 5b, for insertion of the toes of shoes to be treated. In my hood the openings 5a are formed in the curved front wall, whereas in ordinary toe heaters the openings are placed in a vertical straight wall facing the operator, and 55

the curved wall extends downwardly on the back side of the hood and away from the operator.

The hood 5 is provided with an inner curved wall 5e substantially parallel with the curved front wall 5a and is provided with openings 5f similar and adjacent to the outer openings 5b. The interior of the hood adjacent the related openings 5b-5f forms a softening chamber S into which the toe of the shoe is inserted during 10 the softening operation.

In the construction shown the casting 2, casting 3, radiator 4 and hood 5 are shown of sufficient length to permit four shoes to be treated simultaneously. In such construction the hood 15 has four openings 5b and 5f in its walls 5a-5e and the adjacent pairs of openings are separated by vertical partitions 5c, which register with partition flanges 4c on the radiator, said flanges 4c extending around the top, bottom, and sides of 20 the radiator and corresponding in size with the end of flanges 4b. The construction described is in effect four separate shoe treating units, each operating entirely independent of the others.

The base plate 2 is provided with air inlet openings 2d so spaced that there is an inlet between each adjacent pair of flanges 4c on the radiator that admits air under the radiator. These inlet openings are of such size as will insure a steady uniform flow of air to each chamber S, the air 30 entering under the radiator and passing up both sides thereof and being heated by direct contact with, and radiant heat from, the radiator.

The expansion chamber E is provided in its 35 top with one or more jet openings 6i to permit the escape of vapor or steam from the expansion chamber into the casing below the radiator; there being a like arrangement of outlets between each adjacent pair of flanges 4b or 4c.

The partitions 4c and end flanges 4b of the 40 radiator 4 "line up" with the partitions 5c and ends of the hood 3-5, and form continuous partitions from the bottom of the radiator chamber to the top of the hood which keep separate the mixture of air and vapor admitted to each compartment or chamber S. The advantage of this 45 design is that if any one or more of the chambers is open (that is no shoe being treated therein), air currents in the room, or from an open window, which may enter the open chamber cannot 50 in any way affect the atmosphere in a chamber wherein a shoe is being treated.

Steam is supplied from a main steam pipe 6, to a distributing head 6x, and passes from this head through a pipe 6a to the inlet 4i of the 55 radiator. The amount of steam is regulable by a valve 6b, and in practice the radiator inlet valve is usually turned to "wide open". Steam escapes from the radiator through an outlet opening 4o at the other end of the radiator and is returned 60 by a pipe 6c to the trap 6d.

Steam is supplied from the head 6x through a pipe 7 to the expansion chamber E, the amount of steam admitted being controlled by a needle valve 7a. The condensate in the expansion chamber E drains down to the collar 2a above partition 2e and thence through pipe 2o into the standard 1.

In operation, full line pressure of 15 to 20 lbs. steam is admitted to the radiator 4; this pressure 70 is held and maintained by the steam trap 6d which opens to allow passage of the condensate only. The condensate passes through the trap into the standard and fills it up to the desired water level, which is determined by the outlet 1e. 75 Opening the needle valve 7a about three-quarters

of one turn will admit steam to the expansion chamber E, wherein expansion of the steam takes place and the consequent water vapor formed escapes upwardly into the casing below the radiator through the jet apertures 6i.

The vapor emerging from the jets mixes with the air and passes upward between the heated fins of the radiator. The heated air rising from the top and sides of the radiator mixes with the vapor, and the air and vapor become thoroughly 10 mixed and interspersed before reaching and entering chambers S in the hood. I preferably adjust and proportion the parts so that a relative humidity of about 100 and a temperature of about 200° F. is obtained within the chambers S. 15

The inner curved wall 5e being heated causes a natural draft or up movement of mixed air and vapor which escape through the curved passage 5s between the curved walls 5a-5e, and pass out the vent 5t provided in the extreme top and rear 20 end of the outer curved wall. This construction is effective for the purpose designed. The vent 5t might be connected to a stack or an exhaust system, without detracting from the efficiency of the softener, because no heated air or vapor can be 25 removed from a chamber S until it has contacted with and passed around the toe of the shoe being treated.

When the toe part of a shoe is inserted in a 30 chamber S of the hood through the top openings 5b-5f the passage between the two curved walls 5a-5e is directly over the rear limit of the portion of the shoe to be heated (approximately the tip line of the shoe).

The relation between the size of the vapor jets 35 6i and the depth of the water seal should be such that the proper amount of vapor and air will be normally directed to the chambers S in the hood; and then if an operator should attempt to get more vapor into the hood and open the needle 40 valve further, the increased pressure in the expansion chamber will break the water seal at the end of the outlet pipe 2o and the excess steam will flow out of the pipe and up the standard and escape through the "vent" openings 2p, and no 45 more than the predetermined correct amount of vapor will escape through the jets. This is a practical safety feature; as an excess amount of vapor will cause precipitation on the insole or upper or both, either of which conditions results in spoilage or "cripples". 50

What I term a "correct amount of vapor" is that amount which when admitted to a chamber S (in which the toe part of the shoe is treated) will produce and maintain such a moist atmosphere within such chamber as will properly soften and mull the shoe box toe stiffener without precipitation or wetting or burning any part of the shoe being treated.

In "setting" or adjusting the vapor control the 60 valve 7a should be turned to a point just below where vapor becomes visible at the hood outlets; and with this adjustment all materials which are used in the shoe making art for uppers, toe stiffeners, linings and innersoles can be treated 65 perfectly and without injury.

In my construction the entire surface of the radiator over which the shoe rests is exposed so that I transmit heat directly to the parts to be softened by direct radiation as well as by convection, and the operation of my softener does not depend in any way upon keeping separated any of the various elements such as air or vapor.

The incoming air streams divide below the radiator, part going to the rear, and part passing 75

up the front thereof, and presumably a larger portion of the incoming air is drawn to the back of the radiator due to suction created by the vapor jets, and I do not keep the air and vapor separated.

5 My heater enables the operator to soften the toe of a shoe up to any desired point and not affect in any way that portion of the shoe adjacent to it. Excess air cannot enter the outer portion of a chamber S while a shoe is being treated, because the shoe practically closes the entire opening in the front of the chamber and the rising streams of air and vapor pass into and through the chamber.

10 15 When the upper is "pulled over" by the "bed laster" and the shoe is inserted in one of the shoe treating chambers, the exposed portion of the box toe stiffener is subjected to direct radiant heat from the top of the radiator and also to the vapor laden heated air which directly contacts with the exposed portion of the box toe stiffener, and the stiffener is thereby quickly softened sufficiently to be lasted.

20 25 While the heater shown has four treating chambers, the number can be varied. In practice I have found that three treating chambers are sufficient to enable the box toe stiffeners to be softened as rapidly as they are required by an operator working at normal speed, but a fourth treating chamber provides a safety margin for unusually fast operators or unusually hard stiffeners.

I claim:

30 35 1. A toe softener comprising a base, a casing on said base, an expansion chamber adjacent the base, a radiator mounted upon the base within the casing, a hood above the radiator having a wall provided with an opening and forming a chamber in which the toe of a shoe to be treated is inserted, means for supplying steam to the expansion chamber and radiator, the hood having an inner wall parallel with the front wall thereof and provided with an opening for admission of the shoe toe, and a vent to the atmosphere for the space between the walls at the end opposite the opening.

40 45 2. A toe softener comprising a base, a casing on said base, an expansion chamber adjacent the base, a radiator mounted upon the base within the casing, a hood above the radiator having a wall provided with an opening and forming a chamber in which the toe of a shoe to be treated is inserted, means for supplying steam to the expansion chamber and radiator, a pipe for conducting condensate from the expansion chamber, and a water seal for said pipe whereby the pressure in the expansion chamber is automatically controlled.

50 55 3. A toe softener comprising a base, an expansion chamber adjacent the base, a casing mounted on the base plate, a radiator within the casing, a hood mounted upon the casing above the radiator and provided with an opening for the insertion of a shoe toe, said base plate being provided with an inlet for air into the casing beneath the radiator, and said expansion chamber having apertures for admission of vapor into the casing below the radiator, and means for supplying steam to the radiator and to the expansion chamber.

60 65 4. In a toe softener as set forth in claim 3, a pipe for conducting condensate from the expansion chamber, and a water seal for said pipe whereby the pressure in the expansion chamber is automatically controlled.

5 10 15 5. A toe softener comprising a base plate, an expansion chamber adjacent the base plate, a casing mounted on the base plate, a radiator mounted upon the base plate within the casing, said radiator having flanges and transverse fins on its top and sides intermediate the flanges, a hood mounted upon the casing above the radiator and having its front wall curved forwardly and downwardly from rear to front and provided with an opening in the curved face of said wall for the insertion of a shoe toe, said base being provided with openings for admitting air into the casing beneath the radiator and said expansion chamber having apertures for admission of vapor into the casing below the radiator, and means for supplying steam to the radiator and to the expansion chamber.

20 6. In a toe softener as set forth in claim 5, said hood having an inner wall parallel with the front wall thereof and provided with an opening for admission of the shoe toe, and a vent to the atmosphere for the space between the walls at the end opposite the opening.

25 7. In a toe softener as set forth in claim 5, a pipe for conducting condensate from the expansion chamber, and a water seal for said pipe, whereby the pressure in the expansion chamber is automatically controlled.

30 35 8. In a toe softener of the character described, a hood having its front wall deflecting forwardly and downwardly and provided with an opening in the front portion for admission of a shoe toe; an interior wall in the hood parallel with the front wall and having an opening for the accommodation of the shoe toe, and a vent to the atmosphere for the space between the walls at the end opposite the opening.

35 40 9. For a toe softener, a casing, a radiator within the casing having end flanges and spaced intermediate flanges projecting beyond the top side and bottom wall thereof and partitioning the casing, and fins on the exterior sides of the radiator intermediate the flanges.

45 50 10. For a toe softener, a casing, a radiator within the casing having end flanges and intermediate flanges projecting beyond the top side and bottom thereof and partitioning the casing, and exterior fins extending transversely across the top and sides of the radiator intermediate adjacent flanges.

55 55 11. A toe softener comprising a base, an expansion chamber adjacent the base, a casing on the base, a radiator mounted upon the base within the casing, said radiator having end flanges and intermediate flanges projecting beyond the top side and bottom thereof to space the radiator from the walls of the casing, and a hood mounted above the radiator and having an open bottom and spaced openings for the admission of shoe toes, and partitions intermediate said openings, the partitions registering with the related flanges on the radiator so as to form a plurality of independent similar shoe treating chambers.

60 65 12. A toe softener comprising a base, an expansion chamber adjacent the base, a casing on the base, a radiator mounted upon the base within the casing, said radiator having end flanges and intermediate flanges projecting beyond the top side and bottom thereof to space the radiator from the walls of the casing, and fins extending transversely across the top and sides of the radiator intermediate the adjacent flanges, and a hood mounted above the radiator and having an open bottom and openings in its front wall for the admission of shoe toes and partitions inter- 70 75

- mediate the openings, the partitions registering with the related flanges on the radiator so as to form a plurality of independent similar shoe treating chambers, the front wall of said hood 5 being deflected forwardly and downwardly, the base plate being provided with inlets for air beneath the radiator and the expansion chamber having apertures in its upper side for admission of vapor into the casing below the radiator.
- 10 13. A toe softener comprising a base, an expansion chamber adjacent the base, a casing on the base, a radiator mounted upon the base within the casing, said radiator having end flanges and intermediate flanges projecting beyond the top side and bottom thereof to space the radiator from the walls of the casing, and fins extending transversely across the top and sides of the radiator intermediate the adjacent 15 flanges, an open bottom hood mounted upon the casing above the radiator and having its front wall deflected forwardly and downwardly from rear to front, and provided with an opening in said front wall for the insertion of a shoe toe, 20 said hood having an interior wall parallel with the front wall and provided with an opening for the admission of the shoe toe, the base plate being provided with air inlets beneath the radiator and the expansion chamber having apertures 25 for admission of vapor into the casing below the radiator; and means for separately supplying steam to the radiator and to the expansion chamber.
- 30 14. For a toe softener, a base having a central depending collar, and air inlet openings at opposite sides of the collar, an expansion chamber connected to said base and extending below the same and having its bottom wall inclined toward the collar, and apertures for the escape 35 of vapor from said expansion chamber, a drain pipe connected with said expansion chamber, means for supplying steam to said chamber, and a water seal for said pipe whereby the pressure in the chamber is automatically regulated.
- 40 15. In a toe softener of the character specified, 45 a hollow standard, a base mounted on the upper end of said standard, an expansion chamber connected with said base and having apertures for the escape of vapor, a drain pipe connected with

said expansion chamber and depending into said standard, a radiator mounted on said base, means for supplying steam to said expansion chamber and to said radiator, and means for conducting condensate from the radiator to said standard; the expansion chamber drain pipe being water sealed by the condensate in said standard.

5

16. In a toe softener of the character specified, a hollow standard, a base mounted on the upper end of said standard, an expansion chamber connected with said base and having apertures for the escape of vapor, a drain pipe connected with said expansion chamber and depending into said standard, a radiator mounted on said base, means for supplying steam to said expansion chamber and to said radiator, and means for conducting condensate from the radiator to said standard; the expansion chamber drain pipe being water sealed by the condensate in said standard, a casing surrounding the radiator, and a hood mounted on the casing above the radiator and having its front wall curved forwardly and downwardly from rear to front and provided with an opening for the insertion of a shoe toe.

10

17. A softener of the character specified, having an expansion chamber provided with restricted orifices for water vapor, a regulated steam supply for said chamber, a drain pipe for condensate connected with said expansion chamber, and a water seal open to the atmosphere for said pipe maintained by the condensate whereby the pressure in the expansion chamber is automatically relieved whenever an excess amount of steam is admitted into the expansion 30 chamber.

25

18. In a toe softener of the character specified, a hollow standard, means for venting the standard to the atmosphere; an expansion chamber supported on said standard and having restricted apertures for the passage of vapor, a regulated steam supply for said chamber, and a drain pipe connected with said expansion chamber and depending into said standard, the lower end of said pipe being sealed by water in said standard whereby excess steam in the expansion chamber will be diverted to the atmosphere.
